UNITED STATES PATENT OFFICE.

BENNET HOTCHKISS, OF NEW HAVEN, AND HENRY SHATTUCK, OF HAMDEN, CONNECTICUT, ASSIGNEES TO BENNET HOTCHKISS.

IMPROVEMENT IN FORGE-FURNACES.

Specification forming part of Letters Patent No. 58,346, dated September 25, 1866.

To all whom it may concern:

Be it known that we, BENNET HOTCHKISS, of New Haven, and HENRY SHATTUCK, of Hamden, both in the county of New Haven and State of Connecticut, have invented certain new and useful Improvements in Furnaces for Heating Metal; and we do hereby declare the following, when taken in connection with the accompanying drawings and the letters of reference marked thereon, to be a full, clear, and exact description of the same, and which said drawings constitute part of this specification, and represent, in—

Figure 1, a side elevation. Fig. 2 is a plan. Fig. 3 is a longitudinal and vertical section on a line in the rear of the front wall.

Our invention has reference to the following particulars, which are intended to adapt the heating-furnace for general use in blacksmith-shops and in establishments where metals are worked: First, in combining together the ordinary forge with a reverberatory furnace, the heat of the latter being derived from the same fire which is employed in the furnace; second, in a better means for cooling the furnace-doors to prevent the injurious effects of heat upon them by the use of a current of air, which may also, after it has performed this office, be used for accelerating the fire-draft; third, in interposing between the workman and the fire, when the furnace-door is opened, an air-blast to keep the flame and gases back from the face of the workman; fourth, in employing the waste heat for raising the temperature of a body of water and applying the vapor to stimulate combustion in the furnace; and, finally, fifth, in employing the same waste heat, in the course of its exit to the chimney, to raise the temperature of a body of air surrounding the smoke-flue, and in applying the same for increasing the fire-draft.

In the accompanying drawings, B represents the forge or furnace, of well-known construction, provided with grate-bars *a a a*, and with a chute, B, through which the coals are introduced. With this furnace is combined a second chamber, C, separated from the first by a transverse partition, I. This partition should be of sufficient height to confine the coals within the grate-surface, but should not be so high as to obstruct the flames from pass-

ing over into the second chamber, which, being completely inclosed, with the exception of the aperture *b* for the escape of smoke and gases, is thereby constituted a reverberatory furnace.

It is evident that metals can be heated in both chambers at the same time, and, as the result of this combination of these two classes of furnaces, the same fire which, by direct action is made to heat metals in the first chamber, is, by the reverberatory principle, made also available in the second chamber; and this second chamber can, if desired, be as readily constructed with a dome or arched roof, for better reflecting the heat, as with the flat roof shown.

Each of the furnace-chambers is provided with a door, E E', operated by a lever and treadle in the usual way. We have introduced, however, an improvement in the method of preventing them from becoming unduly heated, which is as follows: The doors are made with outer and inner plates, between which is an air-space. An air-blast is introduced into this space by means of the nozzle F, which may be connected by a flexible tube with a suitable bellows for the purpose. An aperture in the edge of each door allows the space between the outer and inner plates to communicate with an opening under the grates-bars by means of channels appropriate to each door, made for the purpose in a projecting vertical piece, G, upon the furnace-front, the edges of which projecting piece also furnish one of the two guides to each door, lateral openings being made in the same, communicating with the vertical channels and corresponding with the lateral openings in the edges of the doors, so that the blast, after it has performed its office of cooling the doors, is conducted under the fire to increase the draft.

We deem it advisable, also, (though a good effect may be produced by constructing the doors with simple double plates and an intervening air-space, as described,) to interpose between the outer and inner plates of the doors a wall of plaster-of-paris, soap-stone, or other non-conductor of heat, leaving air-spaces between each side of the same and the door-plates, for the circulation of the blast of air

which is to be introduced. This arrangement will insure a greater degree of durability to the doors, and need not at all interfere with the arrangement described for conducting the blast underneath the grate-bars.

A similar and perhaps as useful effect, without the aid of a blast, can be produced by making the doors of simply an outer and inner metallic shield or plate, separated from each other the usual distance by stud-bolts, the outer plate being perforated with holes sufficient in number and size to allow the outside air to enter, and, after cooling the plates, be drawn, by the method already described, into the furnace.

In this latter arrangement it will be necessary to have a chimney of sufficient height to cause a draft powerful enough for the purpose, and then, in addition to the principal effect designed, there will be the incidental advantage obtained of a means for ventilating the atmosphere of the room.

Another feature of our invention consists in interposing a blast of air between the workman and the furnace when the door is raised, which will, as its force is directed against the fire, keep the flames from belching out and blinding his eyes with smoke and gases.

For this end, we place in front of the furnace-door a horizontal pipe, H, which, by any suitable and convenient means, is connected with an air-blast. This pipe has a longitudinal slit cut in one side, which is covered, when the blast is not required, by the sleeve H', fitted to turn on the pipe H. This sleeve has also a similar slit cut in its side, so that when the sleeve is turned on the pipe far enough to cause the two slits to correspond a blast of air will be directed against the furnace-door.

This device is, in effect, an ordinary stop-cock, and may be variously arranged to let on or cut off the blast, as desired; and while the device itself is well known, the application of it for the purposes described is both novel and useful.

It has already been stated that the aperture b in the reverberatory chamber is intended for the escape of the smoke and gases generated by the combustion of the fuel in the furnace A. Inasmuch as a considerable amount of heat will also at the same time pass off, it is desirable to utilize the same as much as possible.

The aperture b is connected by a smoke-pipe, I, with the flue J', arranged, by preference, beneath the surface of the ground and leading to the chimney. This smoke-pipe I is surrounded by a close cistern, K, partially filled with water. There is a pipe, d, near the top of this cistern, above the water-line, leading to a point underneath the grate-bars, through which the vapor from the water, as the temperature of

the latter is raised by the heat from the smoke-pipe I, will be permitted to pass into the furnace and stimulate combustion.

We also, for the purpose of further augmenting the draft automatically, surround the ground-flue J' with a jacket or second pipe, L, between which and the outside of the flue-pipe is an air-space. It is evident that the air in this surrounding space will soon become of the same temperature, or nearly so, as the metal which composes the smoke-flue. This heated air is also discharged underneath the grate-bars by means of a pipe, e, conveniently arranged, a constant circulation being maintained by means of a supply of cold air, which is admitted into the space through suitable openings made for the purpose, and communicating in any convenient way with the atmosphere.

Instead of surrounding the flue completely with the air-chamber, the same effect in kind, though less in degree, will be produced by partially surrounding it with such chamber—as, for instance, where the cross-section of the flue is rectangular instead of circular, the air-chamber may be arranged along the top or one or more of its sides.

We do not mean to limit ourselves to the precise construction and arrangement of the several parts as described, but mean to include all mere variations of form, structure, and arrangement accomplishing the same effect by substantially equivalent means.

What we claim as our invention, and desire to secure by Letters Patent, is—

1. Combining a forge, A, with a reverberatory furnace, C, in the manner substantially as described, for the purpose specified.

2. Applying a current of air, whether set in motion by an artificial blast or by the chimney-draft, to cool the furnace-doors and to furnish a draft to the fire, in the manner substantially as described.

3. The use of an air-blast to prevent the flames and gases from belching from the furnace when the door is open, arranged and applied substantially as described.

4. The combination of a cistern, K', arranged as described, with the furnace A, for the purpose of converting into vapor a body of water by the waste heat of the furnace, and applying such vapor to stimulate combustion, substantially as set forth.

5. Combining with the escape-flue J' a space, L, for the circulation of air, and connecting the same with the furnace for aiding the draft of the fire, substantially as described.

BENNET HOTCHKISS.
HENRY SHATTUCK.
